UNITED STATES PATENT OFFICE

HERBERT M. TYNER, OF NEW YORK, N. Y., AND BYRON L. SMITH, OF BROCKTON, MASSACHUSETTS; SAID SMITH ASSIGNOR TO SAID TYNER.

RUBBER HEEL

Application filed June 16, 1928. Serial No. 285,812.

This invention relates to rubber heels.

One object of the invention is to provide a device of the character described having a base portion for permanent attachment to a shoe, and a resilient tip fitted in a seat of the base and permanently mounted on the base by improved means that permit the tip to be rotated to present a new wearing surface at the rear end of the heel whenever desired.

10 Another object of the invention is the provision of a device of the nature set forth having a base portion for permanent attachment to a shoe, a resilient tip fitted in a seat of the base and adapted to take the impact of the pavement, anchor members in the base and the tip permanently securing the same together and nevertheless permitting the tip to be rotated to present a new wearing surface at the rear thereof, the tip having a shoulder associated therewith in an improved manner and with the anchor means in the base so as to have vertical abutment relation with the base anchorage and also to re-enforce the engagement of the tip with its anchor member.

15 A further object of the invention is to produce a device of the class specified comprising a base adapted for permanent attachment to a shoe and having a seat adjacent to its tread, which seat is of circular form and defines the rear side of the breast portion of the base, rendering said side of arcuate form and with the base terminating in short side flanges, a resilient circular tip being fitted in said base and mounted for rotation therein, the base having a portion projecting beyond said seat between the plane of the seat and the upper face of the base, the portion last referred to permitting the heel to be uniformly buffed to fit shoes of various forms and without injury to the circular tip nor to the side flanges aforesaid.

20 Still another object of the invention is to provide a device of the species alluded to comprising a base for permanent attachment to a shoe and having a seat adjacent to its tread in which seat a resilient circular tip is fitted for rotatable coaction therein, there being an anchorage between the tip and base permanently securing the two together as a unit, the

anchorage including an improved bearing construction to facilitate the rotation of the tip as aforementioned.

25 Still another object is to provide a device of the type mentioned having a base for permanent attachment to a shoe and a resilient circular tip fitted in a seat of the base and adapted to receive the impact of the pavement, said tip being permanently rotatably mounted in said seat, and there being registering holes in the tip and base to permit fasteners to pass through the tip to secure the base to a shoe.

30 Still a further object of the invention is to provide a device of the character described wherein a resilient circular tip is rotatably mounted in the seat of a base which is adapted to be permanently attached to a shoe, there being improved means provided at the seat between the tip and the base to prevent unintended relative rotation between the parts.

35 Other objects and advantages of the invention will become apparent as the specification proceeds.

40 With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

45 In the drawing:

50 Figure 1 is a side elevation of a heel embodying the invention and showing the same attached to a shoe and before the buffing operation.

the same is attached to the tip anchor member.

Fig. 10 is a top or inside plan view of a tip showing a modification of the invention.

Fig. 11 is a bottom plan view of the base made according to the modification referred to.

Fig. 12 is an enlarged fragmentary vertical section taken on the line 12—12 of Fig. 11.

Fig. 13 is a section taken on the line 13—13 of Fig. 12.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

According to this invention the tip is mounted in permanent engagement with the base of the heel, permitting the employment of improved simplified fastening means which are nevertheless absolutely rugged and reliable in use. In this way all possibility of accidental or unintended detachment of the tip from the base of the heel which may occur where the fastening means permits detachment of the tip in one way or another, is eliminated. By this invention the stud of the tip is of hollow form and is headed over the anchor plate in the base. A washer is provided between the anchor plate and the head of the stud so that the rotation of the tip may not be frictionally impeded. This washer, furthermore, preferably has an opening of slightly smaller diameter than the opening in the anchor plate so that on heading over the stud the latter will not be caused to grip or engage the anchor plate. The tip has an integral shoulder concentric with the stud and extending into an opening in the base so as to have vertical abutment relation with the base anchor member. This prevents vertical movement of the stud with respect to the anchor member referred to and accordingly any squeaking that might result from said movement where the metal parts have rusted, is prevented. A second washer may be positioned between the shoulder and the anchor member of the base so as to prevent any rubber from forcing its way to the bearing of the stud. To prevent unintended relative movement as between the tip and the base the former is provided with a plurality of concentric pits and the latter with one or more projections to selectively engage in said pits. This feature of the invention, however, may also be embodied in a concentric series of notches or ridges formed in

the tip to engage selectively with a plurality of similar notches or ridges on the base at the rear portion thereof. To facilitate attachment of the heel to a shoe the base and tip are provided with registering holes so that fasteners can be passed through the holes in the tip and thence into the base to secure the latter to a shoe. In order to permit the heel to be used with shoes of various forms, the base is provided with a projecting portion between the planes of the seat and upper surface thereof which projecting portion is buffed down to suit the size and form of the shoe. This projecting portion likewise prevents the tip from being buffed and consequently from losing its true circular quality. Likewise it safeguards the short side flanges of the base from being damaged during the buffing operation. It has notches that act as a guide and facilitate accurate positioning of the heel on the shoe before nailing, the said notches also indicating the maximum depth of buffing.

Referring in detail to the drawing 15 denotes a device embodying the invention. The same is seen to comprise a heel attached to a shoe 16 and prior to the buffing operation. The heel 15 includes a base 17 which may be made of any suitable material well known in the art but preferably of rubber. The said base has an upper surface 18 that is normally glued to the leather heel portion 19 of the shoe and a tread portion 20. At its front end the base is formed with a breast portion 21 and it includes a circular seat 22 that extends from the breast portion to the rear end of the base. Accordingly the breast portion comprises an inner arcuate wall 23 and terminates in the rearward extending side flanges 24.

Molded in the base is an anchor plate 25, the same being preferably positioned between the surface 18 of the base and the seat 22 thereof. Said plate is of circular form and is preferably concentric with the seat referred to. In the center of the plate is an opening 26 to receive the stud as hereinafter described. A plurality of relatively large openings 27 are formed in the plate through which rubber may flow so as to strongly secure the anchor plate in the heel base. In proximity to the periphery of the anchor plate are a plurality of nail or fastener holes 28 surrounding which are the cup depressions 29 which in the finished heel extend substantially to the surface 18 of the base and provide substantially sharp edges to bite into the permanent heel seat of the shoe.

Concentric with the bearing hole 26 are a pair of openings 30 and 31 in the surface 18 and seat 22, respectively, thus exposing the central portion of the anchor plate. These openings have improved co-operation with the fastening means as hereinafter described.

The tip 32 is of circular resilient nature and may be made of any desirable material, as for

example, rubber. It is snugly fitted in the seat of the base 17, being provided with an upper surface 33 which may be slightly concave to afford tight contact with the seat 22 at the periphery thereof. The tip is also provided with a tread 34 which forms a continuation of the thread 20 of the heel base.

Molded in the tip is an anchor member 35 which may be of circular form and has a central opening 36 concentric with the tip. Adjacent to the periphery of the anchor member are a plurality of openings 37 through which the rubber may pass to strongly engage the anchor plate 35 in the tip and also to strengthen the latter. A stud 38 has an undercut end 39 that passes through the hole 36 and is headed or bradded thereover to form an absolutely rigid engagement with the member 35 as is clearly shown in Fig. 3. Accordingly after the molding operation has occurred, the tip has a coaxial stud which projects therefrom so as to be adapted to take into the hole 26 in the base anchor member. In course of the molding of the tip an opening or recess 40 may be formed in the tip of the tread portion thereof to permit the insertion of a supporting member for the stud which is necessary when the latter is to be headed over for permanently mounting the tip on the base.

Coaxial with the stud and extending therearound in proximity thereto is a circular shoulder 41 which is preferably integral with the tip and extends upward of the surface of the tip into the opening 31 of the base so as to have vertical abutment relation with the anchor plate 25. A washer 42 may extend around the stud and be positioned between the shoulder 41 and the anchor plate 25. This washer preferably has tight or snug contact with the stud so that none of the material of the shoulder may through pressure flow into the stud bearing. Due to the shoulder feature of the invention, all vertical movement of the stud with respect to the base anchor plate is prevented except perhaps in a very slight degree due to the elasticity of the rubber. Accordingly the squeaking action that formerly obtained where the upper surface of the tip was of marked concave form resulting in a comparatively considerable upward movement of the stud when the wearer placed his weight on the heel, and rusted metal parts would rub against one another, is eliminated. Furthermore, the shoulder 41 acts as a reinforcement for the tip and prevents the anchor member 35 from being pulled out of the tip when the latter is flexed or rotating the same. It may be noted that the shoulder 41 is of slightly larger diameter than the anchor member 35 so that the reinforcement action is therefore rendered considerable.

To permanently mount the tip on the heel base, the stud is headed over as shown at 44 by any suitable machinery provided for the

purpose and thus forms a uniform circular bearing. A washer 45 between the anchor plate 25 and the headed portion 44 of the stud, has a hole of slightly smaller diameter than the hole 26 so as to take up any lateral expansion of the hollow stud when the same is peened over and prevent the same from binding against the plate 25. It will be noted that the opening 30 is of sufficient depth to insure a slight space between the headed portion 44 of the stud and the adjacent surface of the shoe so that the stud itself may preferably not contact the shoe.

To prevent unintended relative rotation between the tip and the base, the former may be provided with a plurality of concentric pits 46 and the latter with one or more lugs 47 at the rear portion thereof to selectively take into the aforementioned pits. In normal operation after the rear portion of the tip has become worn, the said rear portion is gripped by the hand and flexed away from the base of the heel to disengage the lug 47 after which the tip may be rotated to bring a new portion of the tip to the rear of the heel and the lugs 47 re-engaged with the pits 46.

To fasten the heel to a shoe the base and tip are provided with a plurality of openings 48 and 49, respectively, that register with the holes 28 in the anchor plate 25. Fasteners or nails may accordingly be passed through the tip and thence driven through the base and into the shoe. In this regard it may be appreciated that the cups 29 constitute a material aid in guiding the ends of the nails into the holes 28. Moreover, the said cups are formed to receive and engage the heads of the nails, and being in contact with the shoe may prevent undue strain on the heel and also permit the cobbler to definitely ascertain when he has fully driven the nails home.

To permit the heel to be attached to shoes of varying forms, the base thereof is provided with a rearward projecting portion 50 between the planes of the upper surface of the seat 22. This projecting portion extends around the sides of a heel base and fades out as shown at 15. Preferably the portion 50 is of triangular form in vertical cross section and with the base of the triangle at the surface 18. It may also have a plurality of notches 52 which aid the cobbler in setting the heel accurately on the shoe. The notches also indicate the maximum depth of buffing, and thus protect the tip. In course of the buffing the side portions 53 of the projecting portion 50 protect the base flanges 24 against injury. It will now be appreciated that by permitting an extremely slight portion 50 to remain after the buffing has been completed, the heel is available for neat use in connection with many shoes of different sizes or forms. In keeping with the spirit of the pro-

jecting portion 50 the sides 54 of the heel base may be straight and parallel and the breast portion 17 may be slightly larger than usual so as to permit the heel to be buffed down at the sides 54 and at the front face 55 of the breast to conform to the shoe as shown in dot and dash lines 56 and 57.

In Figs. 10 to 13 is shown a modification embodying the invention. This heel is in all particulars the same as that hereinbefore described with the exception of the means between the tip and the base of the heel for preventing unintended relative rotation therebetween. In this embodiment the said means takes the form of a concentric series of notches or ridges 60 in the tip 61, while the base 62 has a plurality of similar notches or ridges 63 adjacent to the rear thereof. The notches 60 and 63 are preferably of radial form and of equal pitch so as to selectively engage one another regardless of the position of the tip. The length of the ridges is considerable so as to provide ample bearing relation. The length of the ridges 60, however, is greater than that of 63 so as to provide end spaces 64 for the reception of any dirt or the like that may accumulate. Preferably the ridges in the base are slightly arc shaped lengthwise so as to have a tendency to press any dirt that may accumulate in the recesses in the tip to the end spaces 64. By this construction if the operator should desire to turn the tip in order to present a new wearing surface at the rear of the heel, it is merely necessary for him to flex the tip 61 at the rear of the heel away from the base 62 and then to rotate the tip to any desired extent. Thereafter the tip is released and will spring back into normal engagement with the base. A multiplicity of the ridges and their comparatively small size insures of proper coaction without the necessity of exerting any particular effort to bring the ridges into mating coaction. Particularly is this the case where the operator has exerted pressure on the heel in the normal course of wearing the shoe. The respective ridges can be inexpensively molded in the rubber and constitute a simple effective and highly convenient means for retaining the tip against unintended rotation with respect to the base of the heel.

It is thus seen that we have provided a device that fulfills the several objects of the invention and is well adapted to meet the conditions of practical use.

We claim:

1. In a heel, the combination of a base, a resilient circular tip to receive the impact with the pavement, an anchorage centrally rotatably securing the tip to the base, a circular series of narrow ridges on the tip in close proximity to each other, said series being concentric with the anchorage, and a plurality of narrow ridges on the base at one portion only thereof to mesh with ridges

on the tip in any angular position of the latter to prevent unintended rotation of the tip, the portion of the tip adjacent to the ridges on the base being adapted to be flexed away therefrom to disengage the ridges and permit the tip to be rotated.

2. A heel comprising a base having an extended rear edge portion adapted to be removed by buffing, said portion having one or more recesses therein to facilitate the accurate positioning of the heel on the shoe and to indicate the maximum depth of buffing.

3. In a heel, a resilient base for attachment to a shoe and a one-piece anchor plate extending along and re-enforcing the base, said anchor plate being spaced from the top surface of the base, said anchor plate having a plurality of holes to receive fasteners to attach the base to the bottom of a shoe, the said anchor plate having portions thereof around the holes bent upward to form cups having relatively sharp edges adapted to be forced into the permanent heel seat portion of the shoe when the heel is attached thereto, whereby a rigid engagement is afforded between the plate and the shoe on close driving of the nails.

4. In a resilient heel, a base, a rubber tip to take the impact with the pavement, the base including a plate having a hole, the tip having an anchorage rotatably securing the tip to the plate, said anchorage comprising a member extending through said hole and having bearing relation therein, the member being headed over the plate, and a washer between the plate and the headed portion of the said member, said washer having snug fitting engagement with the member to prevent the latter from binding against the plate on being headed over as aforesaid.

5. In a resilient heel, a base, a rubber tip to take the impact with the pavement, the base including a plate having a hole, the tip having an anchorage rotatably securing the tip to the plate, said anchorage comprising a member extending through said hole and engaging over the plate, and a washer about the member positioned between the tip and said plate to prevent rubber from being squeezed into said hole.

6. In a heel, a base having a breast portion and a seat adjacent to its tread, said seat extending from the breast portion to the rear end of the heel, and a rotatable tip fitted in said seat and closely contacting the breast portion, said base having a rear edge portion extending beyond the seat and adapted to be removed by buffing, said portion having one or more recesses therein to indicate the maximum depth of buffing, as set forth.

7. In a heel, a base having a breast portion and a circular seat adjacent to its tread, and a tip rotatably mounted in said seat in close contact with the breast portion, said

breast portion terminating at the sides of the heel in narrow flanges projecting toward the rear of the heel, the base having an edge portion beyond said seat, at the ends of said flanges, said edge portion being adapted to be buffed and having recesses therein to facilitate the accurate positioning of the heel on the shoe and to indicate the maximum depth of buffing, as set forth.

10 8. The herein described method which includes forming a projecting portion on the rear part of the stationary member of a rotatable rubber tip heel, and indicating means on said portion associated therewith, attaching the heel to a shoe, and buffing said projecting portion to the depth indicated by the indicating means.

9. In a heel, a resilient base for attachment to a shoe, an anchor plate secured to 20 the base, a rotatable resilient tip, and bearing means permanently securing the tip centrally to the plate whereby the tip is rotatably mounted in close association with the base, the base having an integral portion 25 underlying the plate, whereby the tip has pressure contact directly with the said portion, the plate having holes for nails for fastening the base of the shoe, the tip having holes registering with the holes in the 30 plate, so that the nails may be driven through the registering holes of the tip and plate, with the heads of the nails engaging the plate in spaced relation to the tip.

In testimony whereof we affix our signatures.

HERBERT M. TYNER.
BYRON L. SMITH.
